US00D855588S

(12) **United States Design Patent** (10) **Patent No.:** **US D855,588 S**
Hao (45) **Date of Patent:** **** Aug. 6, 2019**

(54) **WIRELESS SPORTS HEADSET**

(71) Applicant: **SHENZHEN DALIYUAN TECH. CO., LTD.**, Baoan District, Shenzhen (CN)

(72) Inventor: **Zhigang Hao**, Shenzhen (CN)

(73) Assignee: **SHENZHEN DALIYUAN TECH CO., LTD.**, Shenzhen (CN)

(**) Term: **15 Years**

(21) Appl. No.: **29/634,827**

(22) Filed: **Jan. 25, 2018**

(51) LOC (12) Cl. **14-01**

(52) U.S. Cl.

USPC **D14/223**

(58) **Field of Classification Search**

USPC D14/223, 205, 188, 192; D24/174; 181/129, 130, 135; 379/430, 431; 381/380, 381, 374; 455/90.3, 575.1, 455/569.1

CPC H04R 25/00; H04R 1/10; H04R 1/1016; H04R 1/1066; H04R 5/033; H04R 5/0335; H04R 25/02

See application file for complete search history.

(74) Attorney, Agent, or Firm — Juan Carlos A. Marquez; Marquez IP Law Office, PLLC

(57) **CLAIM**

The ornamental design for wireless sports headset, as shown and described.

DESCRIPTION

FIG. 1 is a perspective view of a wireless sports headset, showing my new design;

FIG. 2 is another perspective view thereof;

FIG. 3 is a front view thereof;

FIG. 4 is a rear view thereof;

FIG. 5 is a right-side view thereof;

FIG. 6 is a top view thereof; and,

FIG. 7 is a bottom view thereof.

1 Claim, 7 Drawing Sheets
